UNITED STATES PATENT OFFICE.

LUCYLE DUVALL ZELL, OF BALTIMORE, MARYLAND.

DESIGN FOR A CHILD'S BLOUSE.

44,718.

Specification for Design.

Patented Oct. 7, 1913.

Application filed July 21, 1913. Serial No. 780,404. Term of patent 7 years.

To all whom it may concern:

Be it known that I, LUCYLE DUVALL ZELL, a citizen of the United States, residing at Baltimore, State of Maryland, have invented a new, original, and ornamental Design for a Child's Blouse, of which the following is a specification, reference being had to the accompanying drawing, forming part thereof.

is a rear or back elevation showing my new design.

I claim:

The ornamental design for a child's blouse as shown.

LUCYLE DUVALL ZELL.
